R. F. MORRISON.
SASH LOCK.
APPLICATION FILED FEB. 25, 1920.

1,412,062.

Patented Apr. 11, 1922.

UNITED STATES PATENT OFFICE.

ROBERT F. MORRISON, OF BATTLE CREEK, MICHIGAN.

SASH LOCK.

1,412,062.

Specification of Letters Patent. Patented Apr. 11, 1922.

Application filed February 25, 1920. Serial No. 361,098.

To all whom it may concern:

Be it known that I, ROBERT F. MORRISON, a citizen of the United States, residing at Battle Creek, in the county of Calhoun and 5 State of Michigan, have invented certain new and useful Improvements in Sash Locks, of which the following description, with appended claims, taken in connection with the accompanying drawing, forms a specification. 10

The present invention relates to sash locks in which a mortise is formed within the window sash and carries an eccentric dog for engaging the window jamb, and the primary object of the invention is to provide a 15 lifting knob connective with the sash stop whereby said stop may be released in its engagement with the window jamb, and also afford means whereby the window sash may 20 be more readily elevated or lowered. Another object of the invention is to insure the action of the stop within itself after a window sash has been raised unless acted upon by an operative. Another object of 25 the invention is to so attach the stop to a window sash that its appearance will not be unsightly nor the stop itself greatly hinder in either finishing the woodwork or washing the same. 30

With these and other objects in view, my invention consists in the novel features of construction, combination and arrangement of parts which will be hereinafter referred to and more particularly pointed out in the following specification and claims. 35

In the accompanying drawings, Figure 1 is a broken side section of a window jamb and window sash, a portion of the sash and sash lock being broken away to show the 40 interior mechanism of the sash lock.

Fig. 2 is a detail edge view of a window sash with my improved sash lock fitted thereto.

Fig. 3 is an end view of my improved 45 sash lock.

Fig. 4 is a broken detail of the locking dog with rubber inserted tip.

Fig. 5 is a plan view of Fig. 4.

Fig. 6 is a plan view of a modified form 50 of a rubber or other friction tip or pad used as the locking dog.

In the drawings, like marks of reference refer to corresponding parts in the different views in which A represents a window jamb, 55 and B, a window sash.

The window sash B is provided with a

mortise 1 and is furrowed out along its edge to permit the inserting of the lock frame 2. The frame 2 on its face side has a longitudinal central opening 3 through which a locking dog 4 operates and has two rounded ends 5 through which screws 6 are inserted and screwed into the window sash B to secure the same thereto. This frame also is formed with oppositely-disposed sides 7 having aligned holes through which gudgeons 8 and 9 form an axle on which the dog 4 is operated. The gudgeon or bearing of the dog on the side of the sash within a room is formed by a reduced end 9 of an operating and lifting knob 10, the gudgeon being screw-threaded into the dog for the purpose of readily permitting said dog to be introduced into its frame, the knob operating through a hole in the sash provided therefor. 60

The dog 4 in operative position extends in a diagonally downward direction toward the window jamb A and is formed with a face eccentric with its axle, and by preference 80 the face of the dog carries a cushion surface of rubber, 11, or equivalent material. The cushion is for the purpose of affording perfect non-slipping contact of said dog with the window jamb, and also precludes 85 scratching or marring of the woodwork. It also renders the operation of the sash lock noiseless. That the dog 4 will always grip the window jamb when the sash has been elevated and released by the operator, a coil 90 spring 2 is coiled about the axle of said dog and one end of said spring anchored within a detent or hole in the side of the frame 2, its opposite end hooked under or lodged within a hole in the side of said dog, the 95 arrangement of the spring being such as will exert a lifting effect on the dog and keep the same in contact with the window jamb.

In Fig. 4 the dog is formed with an undercut recess or groove 13 providing an anchorage for a depending rib 14 of the rubber facing 11, whilst in the views shown in Figs. 1, 2 and 3, the facing is of a uniform thickness, having four ears 15, (shown in outline in Fig. 6), said ears when the facing is fitted on the face of the dog, bent downwardly and secured by small rivets 16. The aforesaid means of attaching the cushion surface to the face of the dog is to insure a more enduring method than would be 110 insured were the same cemented thereto.

In operation, when a sash is elevated in

- its jamb, the same may be raised in the ordinary manner or the same may be elevated by pushing upwardly on the sash top girt and with the other hand lifting on the knob.
- 5 10. If the knob 10 is used for lifting purposes, the same may be slightly rolled to relieve the dog from engaging the window jamb antecedent to lifting thereon and when the sash has been sufficiently elevated
- 10 15. to relieve said knob and permit the dog 4 to engage said jamb, the eccentric mounting of the dog always insures its grip on the jamb in a downward movement of the sash when the knob 10 is unrestrained.
- 15 20. From the foregoing description, taken in connection with the accompanying drawings, a more extended explanation of the objects and advantages of my invention is believed not to be necessary.
- 20 25. Having, therefore, set forth my invention, what I claim as new and desire to secure by Letters Patent, is:—
1. In a sash lock, the combination with the window jamb and a sash slidably movable therein, said sash having a mortise in an edge abutting said jamb, a bracket carried within said mortise, a gudgeon journaled in said bracket extending through one side of said sash, an eccentric dog af-
30 35. fixed to said gudgeon and adapted to lock with said window jamb when said sash is lowered and to release said window jamb when said sash is elevated, and a knob on said gudgeon to actuate said eccentric dog as expedient.
2. In a sash lock, the combination of an eccentric-shaped dog having a centrally-disposed longitudinally-undercut face, and a friction pad of rubber or equivalent mate-
40 45. rial having a depending rib adapted to interlock within said longitudinally-undercut face, as and for the purpose set forth.
3. In a sash lock, the combination with a window jamb, a sash slidably mounted therein, the sash having a mortise in its edge and a housing bracket carried in said mortise, of a gudgeon journaled in said bracket, an eccentric dog affixed to said gudgeon adapted to lock with said window jamb in the lowering of said sash and to release said window jamb when said sash is elevated.
4. In a sash lock, the combination with a window jamb, a sash slidably mounted therein, the sash having a mortise in its edge and a housing bracket carried in said mortise, of an operating gudgeon journaled in said bracket extending through said sash, an eccentric dog operative from said gudgeon and adapted to bear against said jamb in a down and outward direction from said gudgeon whereby said dog will lock with said jamb unless released therefrom, in the downward movement of said sash.
5. In a sash lock, the combination with a window jamb, a sash having a mortise in its edge and slidably movable in said jamb, a housing frame carried in said mortise, of an eccentric-shaped dog having a gudgeon on one side adapted to seat in a side hole in said frame, an operating knob extending through the opposite side of said frame having a reduced threaded end screw-threaded into the opposite side of said dog forming an oppositely-disposed gudgeon, 70 75. said dog adapted to project from said frame to engage said jamb, and means to yieldingly hold said dog against said jamb, for the purpose set forth.

ROBERT F. MORRISON.
